UNITED STATES PATENT OFFICE

FRANK KEIDEL, OF ELMHURST, NEW YORK, ASSIGNOR TO THE INTERNATIONAL SEAL AND KNOT PROTECTOR CO., OF NEW YORK, N. Y., A CORPORATION OF NEW YORK

SEAL

Application filed November 9, 1929. Serial No. 405,894.

This invention relates to seals, and the preferred embodiment involves features broadly covered in my co-pending application, filed February 23, 1929, Serial No. 341,965.

5 My improved seal is of the type in which the relatively movable parts will automatically lock to sealing position after being applied to an article to be sealed, and when in sealed or locked position, cannot be opened 10 without mutilation thereof to such a degree as will render the seal unfit for further use.

One object of the invention is to provide a novel seal which may be formed from a single piece of metal bent to form the several 15 elements of the seal, thereby providing an article which may be manufactured for comparatively small cost.

Other advantages will be pointed out more particularly hereinafter or will be apparent 20 from an inspection of the embodiment illustrated in the accompanying drawings.

In the drawings which illustrate two forms on an enlarged scale—

Fig. 1 is a perspective view of one form of 25 my seal,

Fig. 2 is a plan view of the blank from which the seal illustrated in Fig. 1 is formed,

Fig. 3 is a perspective view showing the blank partially bent to form the seal,

30 Fig. 4 is a perspective view showing the complete seal ready for use,

Fig. 5 is a transverse sectional view taken on the line 5—5 of Fig. 1,

Fig. 6 is a plan view of a blank from which 35 a second form of the seal may be made,

Fig. 7 is a perspective view of the seal constructed from the blank shown in Fig. 6, before the same has been closed, and

40 Fig. 8 is a perspective view of the last mentioned form of the invention after the seal has been closed.

In that form of the invention illustrated in Figs. 1 to 5 inclusive, the seal is substantially triangular in longitudinal sectional shape. The seal comprises a housing section 10, a closure section 11 adapted to fold to position and close the housing 10, and an inner locking section 12, all formed from the same sheet of metal and connected end to end and each of channel shape. The hous-

ing section 10 is the middle section and includes a body portion and extensions which may be bent upon the dotted lines 15 to form side walls 14. At one end of each extension is a slit 16 to provide small sections 17 bendable upon the dotted lines 18 to provide an end wall for the housing 10.

The end section 12 which is adapted to fold within the housing 10 is connected to the latter by an intermediate section 22. The 60 sections 12 preferably has extensions 20 which when bent upon the dotted lines 20 form side walls for this section. The intermediate section 22 is rectangular in shape and of a width substantially equal to the width of the sections 17 and of a length less than the width of the part 10. After the sections 17 and the walls 21 have been bent to the position shown in Fig. 3, the section 22 is bent upon the line 23 so that it also forms an end wall 70 for the housing 10 and occupies a position closely adjacent the sections 17. The section 12 is then bent upon the dotted line 24 to a position within the housing 10 with the wall 12 substantially in the plane of the upper edges of the walls 14, as shown in Fig. 4.

The closure section 11 has tapered side extensions 27 which when bent on the dotted lines 29 form side walls 28. Each of the side walls 28 is provided with an edge portion 30 80 bent to form inturned flanges upon the side walls 28 of the closure section 11. The section is wider than the section 12, but narrower than the section 10.

The closure section 11 is bent upon the line 85 32 to position shown in Fig. 4 and the seal is then ready for application to the article to be sealed. In use, to enclose the knotted end A of a tying cord, shown in dotted lines in Fig. 1, said end is placed within the housing 10 with the cords extending therefrom at the point of bend of the closure section. If desired, notches, such as 33, may be provided to prevent pinching of the cord by the side walls of the closure section. If now, the 95 closure section be further bent upon the line 32, its side walls 28 pass between the side walls 14 of the housing 10, and the side walls 21 of the infolded section 12, until the in-turned flanges 30 engage beneath the edges 100

of the side walls 21 of the inturned section 12. The closure section 11 may extend slightly beyond the side walls 28 and terminates flush with the end of the housing when the closure member is moved to closed position, and this end portion may be beaded down to snugly engage the top of the wall 12 to prevent the insertion of a tool or knife blade therebeneath.

It will be noted that the closure section 11 embraces the infolded section 12 to protect the locking engagement of the inturned flanges 31 with the edges of the walls 21 of the infolded section 12, and prevents releasing of this locking engagement without mutilation of the parts to such an extent as would render them unfit for further use. It will be understood that the spacing of the walls 21, 14 and 28 is shown somewhat exaggerated in Fig. 5.

In the form illustrated in Figs. 6 to 8, the seal comprises a rectangular housing section 40, a section 41 adapted to fold thereinto and a closure section 42, each of which is similar to its respective member in the heretofore described form of the invention.

This type of seal is formed from a blank, such as shown in Fig. 6, shaped to provide the several members 40, 41 and 42. The member 41 is formed from the main body portion 48 of the blank by folding the same along the dotted lines 44 to provide upstanding side walls 45. Slits 46 provide end wall sections 46' for the housing section 40, which end walls are bent inwardly upon the dotted lines 47.

The infolding section 41 has a body portion 48 and side walls 49 formed by bending portions upon the dotted lines 50. After the side and end walls of the housing section 40 have been formed, this infolding member is bent upon the dotted lines 50' and 51 to position it within the housing 40 as in Fig. 7.

The closure section has a body portion 52 and side walls 53 formed by bending upon the dotted lines 54. Each of the portions 53 has an edge portion 55 bent to provide inturned flanges 56. The portion 52 is connected to the portion 43 by a neck portion 57. When the blank is bent upon the dotted line 58, said neck portion will engage the adjacent end wall portions 46' as in Fig. 7.

When employed as a means for protecting the knot of tie strings, or where the article to be sealed is in the form of two strands of cord, wire or the like, the secured ends of the strands may be placed within the housing 40 with the strands extending through the corners as in Fig. 1 or through openings 60 and 61, as shown in Fig. 8. The openings may be in any desired position.

The seal is closed by bending the closure section upon the dotted line 62 until it is positioned within the housing section 40. The locking of the closure section is effected in

the same manner as in the heretofore described form of the invention.

The only places in which a tool or knife blade may be inserted in the form shown in Fig. 1 to force the seal are between the walls 14 and 28 or the walls 11 and 12. The wall 14 cannot be pried out as it is held by the walls 17, and the tool will force the interlocked walls 28 and 21 closer together. The wall 11 cannot be pried up as it is locked by the engagement of the edges of the walls 21 and 28. The seal cannot be opened without breaking or mutilating the parts. The same applies to the form shown in Figs. 6, 7 and 8.

While in the present instance, the invention has been illustrated as applied to a seal for protecting the knots of tie strings or the like, it is to be understood that it may be carried out in many other embodiments and that the details of construction and the design and relative proportion of parts may be varied within comparatively wide limits in accordance with the character of the article or articles to be sealed without departing from the spirit of the invention. For example, the housing section and the closure section may, if desired, be so shaped as to receive and enclose the coupling union of a pipe, in which case it would only be necessary to provide openings in the side walls of the housing section 10 and the closure section 11 to receive the pipe on opposite sides of the coupling.

It will be noted that in my improved construction there is no drawing or stretching or crimping of the metal, the only operations being simple bending of the proper shaped blank on straight lines. Thus it may be made at very low cost by simple and inexpensive apparatus without the use of any complicated or costly dies.

Having thus described my invention, what I claim as new and desire to secure by Letters Patent is:

1. A seal including a main section, a section at one end adapted to fold thereinto, and having side walls spaced from the side and bottom walls of the housing section, and a section at the other end of the housing and adapted to form a closure for the housing, said closure section being engageable with the side edges of the first mentioned end section to lock the closure section in closing position.

2. A seal including a main section, an end section adapted to fold thereinto and having inturned side walls spaced from the side and bottom walls of the housing section, a second end section adapted to form a closure for the housing and having side walls adapted for interengagement with the side walls of the first end section between the latter and the sides of the housing to lock the closure section in closing position.

3. A seal including a main section forming

- 8 a housing to receive an article to be sealed, an end section adapted to fold thereinto and having side walls spaced from the side, and bottom walls of the housing, a second end section forming a closure for the housing and having side walls terminating in inturned flanges for engagement beneath the edges of the side walls of the infolded section to lock the closure section in closing position. 70
- 10 4. A seal including a central section and two end sections each of channel shape in cross section, one end section being narrower than the central section and adapted to fold thereinto with its side walls spaced from the 15 side walls of the center section, and the other end section being wider than the first end section and narrower than the main section and adapted to fold over with its side walls between the side walls of the center section and 20 the side walls of the infolded end section, and means on said side walls of said end sections for locking together the two end sections independent of said main section. 85
- 25 5. A seal including a main section adapted to form a housing to receive an article to be sealed, a relatively smaller section adapted to fold thereinto and having side walls spaced from the side and bottom walls of the housing section, a section forming a closure for the 30 housing and having side walls adapted for position between the side walls of the housing and the side walls of the infolded section, the side walls of the closure section having flanges for engaging the inner edges of the side walls 35 of the infolded section. 90
- 35 6. A seal including a main section adapted to form a housing to receive an article to be sealed, a section adapted to fold thereinto, and a section adapted to fold into the housing 40 section and form a closure therefor, and adapted to embrace the infolded section to lock the closure section in closing position. 95
- 45 7. A seal including a housing section, a second section adapted to fold within the housing and having depending side walls spaced from the side and bottom walls of the housing section, a closure section having side walls adapted to pass between the side walls of the housing section and of the inturned section 50 when the closure section moves to closing position, and inturned flanges formed on the side walls of the closure section for engagement beneath the side walls of the inturned section to lock the closure section in closed 55 position. 100
- 55 8. A seal including a main section adapted to form a housing to receive an article to be sealed, a section adapted to fold thereinto, and a section adapted to fold into the housing 60 section and form a closure therefor, and adapted to embrace the infolded section, and inturned flanges on the closure section to interlock with the infolded section and within the housing section to lock the closure section in closed position. 105
- 65 9. A seal including three sections of channel shape end to end, both end sections being adapted to fold into the middle section, and means on the sides of the two end sections and interengaging to lock together the end sections within the center section. 110
